UNITED STATES PATENT OFFICE.

ALLEN W. SWIFT, OF ELMIRA, NEW YORK.

LUBRICATOR.

SPECIFICATION forming part of Letters Patent No. 283,981, dated August 28, 1883.

Application filed June 13, 1882. (No model.)

To all whom it may concern:

Be it known that I, ALLEN W. SWIFT, of Elmira, in the county of Chemung, in the State of New York, have invented new and useful 5 Improvements in Lubricators, of which the following, taken in connection with the accompanying drawings, is a full, clear, and exact description.

This invention relates to the class of lubricators which are designed chiefly for lubricating the valves and cylinders of steam-engines, and are rendered automatic in their operation by a gradual admission of water to the interior of the lubricant-cup, displacing therein a corresponding quantity of the lubricant, and forcing the same through the lubricant-duct to the steam-pipe, which latter carries the lubricant to the steam-chest and cylinder of the engine.

The object of my present invention is to provide a lubricator which shall be simple and less expensive in construction, and in some respects more efficient in its operation than those hitherto introduced to the trade; and it consists in the novel construction and combination of its 25 constituent parts, as hereinafter fully described, and specifically set forth in the claims.

The invention is fully illustrated in the annexed drawings, in which Figure 1 represents a vertical transverse section of the lubricator 30 and its connection with the steam-pipe, and Fig. 2 illustrates modifications of the details of its construction.

A denotes the lubricant reservoir or cup, which, for greater strength and security against 35 breakage, I construct of metal, and provide the side or front of its upper portion with an observation-port, r, covered by a glass or other suitable transparent plate, as intimated in my prior patent of March 21, 1882, but reserved 40 for special protection in my present application for Letters Patent. Said cup may be of any desirable form, though preferably to have a cylindrical body, through the axial center of which is extended a bolt, C, by means of which 45 the cap D and base E are secured to the body of the lubricant-cup. The lower extremity of the bolt C is bored out to form a central channel, which by an aperture in the side of the bolt communicates with the base of the interior of the cup A. A stop-cock, F, applied 50 to the under side of the lubricant-cup and com-

municating with the aforesaid channel of the bolt C, serves to draw off the surplus water in the cup A. To the top of the cap D is rigidly secured an arm, B, the free end of which is 55 adapted to be connected to the steam-supply pipe S of the engine, and thus sustains the lubricator in its position.

Longitudinally through the supporting-arm B is extended the usual oil channel or duct, a, 60 which communicates at one end with the steam-pipe S, and at the opposite end with the top portion of the interior of the lubricant-cup. The arm B is also provided with a short horizontal steam-channel, b', in the end, which taps 65 the steam-pipe S, and with a vertical steam-channel, b², extending through the opposite end of said arm in range with the center of the coupling-bolt C. Said channels b' and b² are connected by a tube, b, the intermediate portion 70 of which is deflected and isolated from the arm B, and thus surrounded by the external air, and is formed of thin metal, so as to more effectually expose to the cooling influence of the surrounding air the steam which enters said 75 tube, thereby making the tube b serve as a condenser of the steam, which enters from the steam-pipe S through the tube b', and passes in a condensed state into the vertical duct b². The upper extremity of the bolt C is provided 80 with a central channel, b³, which communicates at its upper end with the channel b², and at its lower end with a lateral tube, c, inserted in the side of the hollow portion of the bolt. Said tube c is extended to the observation-port r, and terminates in proximity to the inner face of the glass cover of said port. The extremity of the tube c, I prefer to provide 85 with a highly-polished face, t, which, by its reflection of the light admitted through the 90 glass of the port r, renders the influx of condensed steam to the interior of the cup A more conspicuous, as specified in my prior patent of March 21, 1882. I do not, however, limit 95 my present invention to any particular form of the end or face of the water-tube c, as it may be either at right angles to the axis of the tube, as shown in Fig. 1 of the annexed drawings, or beveled or oblique to the axis of the tube, or inclined toward the glass plate in front 100 of it, as shown in Fig. 2 of the drawings. My invention therefore embraces the feature of

the water-tube *c* with an inclined end or face as well as with any other suitable face, in combination with the metallic cup having a transparent observation-port in front of said tube.

5 The lubricant is introduced in the cup *A* through a suitable inlet at the upper portion thereof, which inlet is provided with a screw stopper, *H*. The water which enters the lubricant-cup *A* through the ducts *b*, *b*², *b*³, and *c* descends to the bottom of the cup and displaces a corresponding quantity of oil, which is caused to ascend and pass through the duct *a* into the steam-pipe *S*, and thence to the steam-chest valve and cylinder of the engine, 15 where it becomes distributed over the valve-seat. The ingress of water and egress of oil are controlled by suitable valves applied to the respective ducts or passages.

Having described my improvements, what I 20 claim as new, and desire to secure by Letters Patent, is—

1. The combination, in a lubricator, of a tube extended from a steam-passage or steam-space to the lubricant-cup, and having its intermediate portion deflected and isolated, to 25 form by its exposure to the air a condenser of the steam passing through it, substantially as set forth.

2. The combination, with a lubricant-cup, 30 of a lubricant-duct and a direct steam-duct, having in common one connection with the steam-pipe of the engine, and the intermediate portions of their lengths isolated from each other, substantially as and for the purpose 35 specified.

3. The combination, with the lubricant-cup *A*, of the supporting-arm *B*, provided with the lubricant-duct *a*, and with the short steam-duct *b*' and vertical duct *b*², respectively, at opposite ends, and the tube *b*, deflected and 40 isolated from the arm *B*, and intersecting the ducts *b*' and *b*², substantially as shown and described.

4. The combination, with the cup *A* and steam-condensing ducts *b*' *b* *b*², of the coupling-bolt *C*, provided with the central channel, *b*³, and the tube *c*, inserted in the side of the hollow portion of the bolt, substantially as described and shown.

5. In combination with the steam-condensing duct and its horizontal extension *c*, the lubricant-cup composed of metal and provided in front of the duct-extension *c* with an observation-port, *r*, covered with a transparent plate, substantially as and for the purpose set 55 forth.

6. In combination with the oil-cup of a lubricator, the port *r*, covered by a glass plate, and the pipe or tube *c*, having an inclined end or face, substantially as set forth.

In testimony whereof I have hereunto signed my name and affixed my seal, in the presence of two attesting witnesses, at Syracuse, in the county of Onondaga, in the State of New York, this 3d day of June, 1882.

ALLEN W. SWIFT. [L. S.]
